UNITED STATES PATENT OFFICE

WARREN E. RIES AND JOSEPH REY, OF MEADVILLE, PENNSYLVANIA

PLIERS

Application filed September 19, 1923. Serial No. 306,991.

This invention relates to combined hand tools of the plier type, and has for its principal object the provision of a tool especially designed to perform all the necessary operations involved in the electrical art, in cutting off non-metallic sheathed cable, cutting the sheath circumferentially, stripping the sheath, and stripping the insulation from the individual wires of the cable.

More specifically stated the invention proposes the construction of a plier tool having jaw plates in pairs, preferably arranged perpendicularly to each other, one pair of plates being preferably disposed at right angles to the longitudinal dimension of the handles, said plates having coacting edges shaped for performing selectively the several functions as above enumerated.

A further object of the invention is the provision of the stripping apertures at a point or points slightly offset from the line of pull so that the pliers are slightly canted with respect to the wire, by the pulling force, thus providing a leading edge for the stripping apertures and thereby facilitating the stripping operation.

Still another object of the invention is to provide the tool with a finger hook between the handles for the purpose of making effective a direct pull upon the pliers, avoiding the need of applying excessive force to the handles of the tool.

Other objects of the invention will appear as the following description of a preferred embodiment thereof proceeds.

In the drawings in which similar parts are designated by the same characters of reference in the several figures,

Figure 1 is a side elevation of the tool,

Figure 2 is a plan view of the same viewed from beneath,

Figure 3 is a side elevation showing the reverse side of the tool, parts of the handles being broken away,

Figure 4 is a front elevation of the tool showing the end plates in closed position,

Figure 5 is a similar view of a slightly modified form, partly in section,

Figure 6 is a perspective view of the pair

of end blades shown in Figure 4 slightly separated,

Figure 7 is a similar view of the side plates,

Figure 8 is a cross section of a sheathed cable of the type with which the present invention is particularly adapted to be used.

Referring now in detail to the several figures, the numerals 1 and 2 designate, respectively, the interfitting plier members, connected by a pivot 3. Said interfitting members are provided with the usual handles 4 and 5 at one end and at the other end with jaws, formed with facets 8 and 9 respectively, for the reception of the tool plates, the facets of each pair lying preferably in the same plane and the pairs of facets being preferably at right angles to one another, one pair being arranged at the ends of the jaws while the other pair is disposed on the lateral face of the jaws on one side. It will be observed from Figure 2 that the jaws are angularly bent in one direction so as to provide room for the end facets.

The side facets are preferably slightly undercut at their peripheral edges so as to dovetail with the two plates which are correspondingly peripherally beveled to enter beneath the undercut edges of the facets.

Referring to Figure 1 it will be noted that the side plates 10 and 11 are slipped into their respective facets from the outward end of the tool and secured in place by suitable means such as the screws 12. The side plates act as cutting elements and are provided for a portion of their length with meeting cutting edges 13, and in the remaining portion of their length they are provided with indented cutting edges 14 and 15 which form the peripheral boundary, when the jaws are closed, of an aperture 16 similar in shape to the cable in connection with which it is used and of smaller cross sectional area than the cross section of said cable.

The operation of this pair of plates is obvious from a description of its construction. When it is desired to sever a length of cable it is placed between the cutting edges 13 and 14 and severed in the usual manner. When it is desired to cut the sheath only of the cable pre-

liminary to stripping the sheath, the cable is placed between the jaws against one of the edges 14 or 15 and the jaws then closed upon it. The edges 14 and 15 penetrate the sheath but since they cannot come together the parts of the cable within said sheath are not disturbed.

The end plates 17 and 18 dovetail with the peripheral edges of the facets in which they 10 seat in the same manner as do the side plates and are similarly secured, for instance, by screws 19. The end plates are provided with cooperating edges designed when the jaws are closed to form an opening somewhat 15 larger in size than the cable. The walls of said aperture are provided at opposite points with cutting elements 21. These may take the form of simple projections, or if desired they may be substituted by the wheel cutters 20 shown in Figure 5. The cable, having had its sheath cut by the edges 14 and 15 of the side plates as previously described, is placed within the aperture 20, and the jaws closed, whereupon the opposed points 21 penetrate 25 the sheath and as the tool is pulled longitudinally of the cable, the sheath is cut through lengthwise, on the upper and lower sides so that it is readily removed, or if the sheath is loose, it is pulled off by the mere engagement of the points 21 with the sheath.

The end plates are also preferably provided with cooperating semicircular edge portions 23 and 24, forming when the jaws are closed combined cutting and stripping 35 apertures for removing the insulation from the individual wires which are in the cable. It is, of course, within the purview of the invention to provide as many of these individual cutting and stripping apertures as may 40 be necessary. In the present instance, only two have been shown, they being of a size capable of operating upon the most popular size of insulated wire, that is to say numbers 10 and 14. However, in practice it is 45 found that one size of cutting and stripping aperture is capable of handling all ordinary sizes of insulated wires.

It will be noted from Figures 4, 6 and 7 that the pair of side blades and pair of end 50 blades are provided at their adjacent ends with interengaging edges 25 and 26 so that in addition to the securing means previously described, the side plates act as a retaining means for the end plates. It is of course obvious 55 that the arrangement of the interengaging edges might be reversed so that the end plates would assist in the retention of the side plates. By this construction a very rigid and reliable construction is provided.

60 It will be noted from Figure 2 that the apertures for cutting and stripping the insulation from the individual wires are offset laterally with respect to a plane passing perpendicular through the pivotal connection 3 at its middle point. This has the effect of

canting the tool slightly when a pull is exerted upon the same in the act of stripping the insulation from a wire. Therefore, instead of the circumferential edge of the stripping aperture acting upon the insulation equally at all points, said aperture assumes an inclined position with respect to the axis of the wire so that one side of the same acts in advance of the rest of the circumferential edge, facilitating the cutting and removal of the insulation.

70 Since in its application as a stripping tool the device of the invention is designed to give a direct pull, means are provided for making this pull effective without the necessity of applying undue squeezing force to the handles of the pliers. In the embodiment as shown this means takes the form of a finger-hook 30 intersecting a plane passing through the pivotal connection and the line of separation of the jaws of the tool.

75 While we have in the above description what we believed to be a preferred and practical form of our invention it is understood that other alternative arrangements and alterations in the construction of the application may be made without departing from the spirit of the invention.

80 What we claim as our invention is:

1. A pivoted tool for performing selective operations upon non-metallic sheathed cable of the type having a plurality of insulated wires comprising interfitting pivoted members including handles at one end and tool supporting faces at the other, blade seats at 100 a side and end of each tool supporting face, blades arranged in cooperative pairs, one pair being slidably inserted in its seat, the adjacent edges of the blades of each pair being constructed to interfit whereby one pair 105 is retained by the other.

110 2. A compound tool for performing selective operations upon non-metallic sheathed cable of the type having a plurality of insulated wires, comprising interfitting pivoted members including handles at one end and tool supporting faces at the other end, blade seats at the side and end of each tool supporting face, blades arranged in cooperating pairs, one pair being slidably inserted in its 115 seat, the side blades being formed with cutting edges while the end blades are formed with cooperating stripping edges the side pair being arranged to overlie the end faces of the end pair, for retaining the latter, and means for securing the end pair in place.

120 In testimony whereof we affix our signatures.

WARREN E. RIES.
JOSEPH REY.
